UNITED STATES PATENT OFFICE.

FLOYD E. MORRISON, OF PHILADELPHIA, PENNSYLVANIA.

DESIGN FOR A DISPLAY-STAND FOR VIALS OF PERFUME.

52,853.

Specification for Design.

Patented Jan. 7, 1919.

Application filed January 31, 1918. Serial No. 214,778. Term of patent 3½ years.

To all whom it may concern:

Be it known that I, FLOYD E. MORRISON, a citizen of the United States, residing at Philadelphia, in the county of Philadelphia and State of Pennsylvania, have invented a new and ornamental Design for a Display-Stand for Vials of Perfume, of which the following is a specification, reference being had to the accompanying drawing, forming a part thereof.

Figure 1 is a perspective view of the display stand illustrating my new design, and

Fig. 2 is an end elevation of the same.

The design consists of a rectangular box, and vertical corners of which are ornamented by angle pieces, the base projecting outwardly and having a rounded edge. At each end of the box is a member forming a perfect figure 7 and having a slot.

I claim:

The ornamental design for display stand for vials of perfume, as shown and described.

FLOYD E. MORRISON.
